CARBURETOR

William E. Leibing, Detroit, Mich., assignor to
 Leibing Automotive Devices, Incorporated, Detroit, Mich., a corporation of Nevada

Application November 6, 1936, Serial No. 109,607

21 Claims. (Cl. 261—41)

This invention relates to improvements in methods and apparatus for operating internal combustion engines, and more particularly to novel methods and means of carbureting such engines.

In present day carburetors at idling speed and at light loads, the fuel fed through the idling jets is not intermingled to any great extent with the air passing through the intake conduit, but instead is fed only at one side in the form of a more or less solid fuel stream while the air is supplied around the entire periphery of the carburetor throttle. Obviously this results in a poor mixture. Further, it has been found that the butterfly valve normally employed as a throttle which is always at an acute angle to the axis of the conduit in which it is mounted, will at speeds where the main jets supply the fuel, divert a major portion of the fuel to one wall of the conduit. All these factors contribute to an unsatisfactory mixture, such factors being the major causes of "gassing", "wet manifold", "unequal distribution" and "power rumble".

In overcoming the aforesaid disadvantages, it is a major object of the present invention to provide a novel carburetor wherein the fuel mixture is delivered concentrically of the intake conduit, and a thorough and complete mixture is obtained at all stages of operation including the idling and light load stages.

It is also a major object of this invention to provide a novel method of setting up the entering air and fuel streams so that the air as originally introduced is substantially in contact with the manifold walls until a complete mixture has been obtained, this method being found to be of tremendous value in eliminating gassing and insuring uniform distribution with a consequent smooth quiet performance of the engine.

Another object of this invention resides in the provision of a novel method and means for insuring degassing in combination with carbureting means which are of relatively simple character.

A further object of the present invention is to provide novel throttling and degassing means that may be readily added to existing carburetor installations with a minimum of alterations.

Still a further object of the present invention is to eliminate the deflection of gas flows to one side of the intake conduit as is usual on prior types of carburetors, and to provide novel means wherein the gas flows are directed in a manner to insure uniformity of mixture.

Further specific and more detailed objects will appear from the following description and the

appended claims taken in connection with the accompanying drawings, wherein:

Figure 1 is a cross section of a down draft carburetor embodying my invention and illustrating in particular the jet for delivering fuel under light loads. 5

Figure 2 is an elevation of the throttle section of Figure 1 illustrating the axes for supporting the throttle blades and the connection to the carburetor pump. 10

Figure 3 is a section taken on the center line of the throttle section of Figure 1 illustrating the arrangement of the fuel jets and their relation to the throttle blades. 15

Figure 4 is an elevation of the connecting means for the throttle blades viewed from the right side of Figure 3 with the casing cover shown at the right side of Fig. 3 removed. 20

Figure 5 is a section taken on a vertical line passing through the idling jet of Figure 3 and 20 looking toward the right of Figure 3. 25

Figure 6 is a perspective of one of the throttle blades of a carburetor embodying my invention.

Figure 7 is a bottom view of the throttle section of Figure 2. 25

Figure 8 is a section of the intake conduit similar to that shown in Figure 3 illustrating a further preferred embodiment of my invention. 30

Figure 9 is a section taken at right angles to the section shown in Figure 8. 35

Figure 10 is a section of a further embodiment of my invention wherein a novel degasser is provided in combination with the carburetor of Figure 1 and means is provided for adaptation of the present invention to carburetors now in use. 35

Figure 11 is an elevation of a part of the device of Figure 10 taken at right angles to Figure 10 and illustrating a novel manner of assembly of the units embodying my invention. 40

Figures 12 and 13 illustrate additional modifications of the degasser and throttle combination shown in Figure 10. 45

Figure 14 is a section of an updraft carburetor illustrating a method of combination of the degasser of my invention with a carburetor employing a throttle of the butterfly type. 45

Figure 15 is an elevation of the edge of the throttle of Figure 14 immediately adjacent the conduit leading to the degasser.

Referring to Figures 1 and 3, I have there shown a preferred embodiment of my invention which may be readily embodied in carburetors now being manufactured and is capable of ready installation on carburetors now in use. A portion of a downdraft carburetor is shown at 11 50 55

with the usual venturi 12, main fuel jet 12', conduit 13, and a float chamber of the usual type generally indicated at F. A throttle housing or section 14 is provided in well known manner and 5 connected to conduit 13 and manifold 15 in the usual manner, a heat insulating gasket preferably being provided between the manifold end section 14.

In the present invention, the conventional 10 throttle of the butterfly type is replaced by a pair of throttle blades 17 mounted to rotate on axes 18 and 19. When the intake is round, the blades are formed with a rounded outer edge. When the intake is rectangular in section or 15 square, the outer edges of the blades are formed accordingly to effect a closure when in closed position. Preferably the throttle section is formed with a conduit having flattened sides as shown in Figure 7 and the throttle blades are 20 shaped to fit. It will be noted that the blades 17 are secured to their axes by screws 21 or similar fastening means, the axes 18 and 19 being formed half round in section and the blades 17 secured to the upper side thereof whereby the axes do 25 not interfere with the fluid flow over the upper surfaces of the blades 17. Axes 18 and 19 are so disposed in conduit 13 that they are each equidistant from the center of the conduit.

It will be noted that the blade construction 30 described closes and opens the conduit simultaneously at each side wall and in the center, thereby giving a three point control of the conduit as a closure along three lines.

Each blade 17 is formed with a half round 35 notch 22 and a half cup 23 on its inner edge as shown in Figure 6, the notches 22 cooperating to form an aperture 24 open when the blades are in closed position as shown in Figure 5, and the half cups 23 cooperating to form a closed cup 40 25 when the blades 17 are in closed position as shown in Figure 1.

Housing 14 is formed with a rib 26 extending thereacross and preferably of stream-line shape as shown in Figures 1 and 5. Rib 26 is formed 45 with a conduit 27 connecting with a fuel conduit 16 preferably connected to the float chamber of the carburetor and opening into jets 28 and 29 that may be termed auxiliary jets. The opening into jet 29 is unmetered, while the opening into jet 28 is preferably metered by a needle valve 31 capable of adjustment by screw 32 in a manner 50 well known in the art.

It will be noted that tube 28 is of less diameter than aperture 24 through which it projects 55 when blades 17 are in closed position as shown in Figure 5, and tube 29 is of a size and length to be entirely enclosed within cup 25 formed when blades 17 are in closed position as shown in Figure 1.

60 Assuming the device to be assembled with an engine and the engine to be running with the blades 17 in closed position as shown in Figures 1 and 5, a very low pressure equal to the pressure in the intake manifold of the engine will be present on the engine side of the blades 17. Remembering that the aperture 24 is somewhat 65 larger than jet 28, a small amount of air at extremely high velocity will be drawn around the end of jet 28. Since jet 28 is directly in the 70 low pressure area, it is subject to both the kinetic energy developed by the injector action of the incoming air around the jet and to the low pressure existing on the engine side as downstream side of the blade 17. Thus a suction of great 75 magnitude is effective on the engine end of jet 28.

As previously pointed out, fuel is delivered from conduit 16 to conduit 27 and thence to jet 28. Were a solid column of fuel brought to jet 28, it would be impossible to adjust valve 31 satisfactorily due to the extremely low pressure effective at the lower end of jet 28. Therefore other means must be employed.

As previously pointed out, as long as blades 17 are closed or nearly closed, cup 25 is formed (Figure 1) the mouth or open side of cup 25 being toward the atmospheric side of blades 17. Jet 29, having its free end within cup 25 on the upstream side of the throttle is therefore exposed to air at atmospheric pressure whenever blades 17 are closed and is free to conduct air into conduit 27. By properly sizing jet 29 and conduit 27, any desired amount of air can be drawn into conduit 27 through jet 29 to obtain a desired air-fuel ratio. Adjusting screw 32 therefore permits both air and fuel to be drawn from conduit 27 through jet 28 and the extreme sensitiveness of the above mentioned solid column of fuel is eliminated.

A further difficult problem in carburetion has always been the progressive movement of the throttle away from the fully closed position. Any movement in this direction immediately requires additional fuel. Since the pressures within the manifold are rapidly rising, a material problem arises in the provision of such additional fuel. During this time the main jets in the carburetor are useless as they have not yet started to function.

In describing the action of blades 17 when they begin to open, let it be assumed that the engine is idling with blades 17 fully closed and the screw 32 to be correctly adjusted to provide the correct air-fuel ratio. The action of blades 17 in correcting the mixture as the flows fall off due to higher pressure on the engine side of blades 17 will now be described.

As discussed above, jet 29 has its open end in an area of atmospheric pressure defined by cup 25 when blades 17 are closed, but as the blades are opened, this cup is no longer at atmospheric pressure, but gradually decreases from atmospheric pressure to the pressure equivalent to that in the engine manifold and even below due to the kinetic energy developed at the end of jet 29 between the opposing ends of blades 17. Therefore by proper proportioning the size of jet 29 to the diameter of cup 25, it is obvious that any degree of progression desired may be readily obtained.

It is apparent to any one skilled in the art that with the present device, the point of least delivery of fuel is when jet 29 has its free end subject to atmospheric pressure where it is free to bleed a maximum amount of air into conduit 27 and to reduce the suction on fuel line 16 thereby, and it is equally apparent that any change from atmospheric pressure to a lower pressure on the jet 29 diminishes the amount of air so bled and therefore increases the actual effective pull on the fuel in fuel line 27. Thus even with a higher pressure in the intake manifold, the fuel fed therein is increased.

This function of jets 28 and 29 is better appreciated when it is considered that modern carburetors have their main jets so designed that they supply only approximately 30% to 40% of the fuel at speeds equal to 2000 to 3000 R. P. M. It is therefore apparent that any improvement in atomization and therefore distribution in the manifold, or any improvement in the method of

obtaining the throttle progression is of extreme importance. Further, any improvement in atomization in closed throttle position is of extreme importance to eliminate gassing for it has been 5 repeatedly proved that gassing is caused primarily by a wet mixture and therefore a wet manifold, the manifold in fact often containing pools of raw fuel which boil out with extreme 10 rapidity under the low pressures caused by deceleration. This boiling off causes the mixture to become rich to an extent that it cannot be consumed by the engine and as a consequence, the engine exhausts this obnoxious gas.

As previously explained, blades 17 are allowed 15 to come tightly together at closed throttle when aperture 24 will supply about 90% of the air required by the engine. The balance of air necessary is supplied by a by-pass 33 which by-passes blades 17 and is provided with a needle valve 34 20 for regulating the air flow.

A further advantage of blades 17 is that as they are opened, they maintain an inclination inward or towards the center in a manner whereby all fuel delivered from the main jet of the carburetor is directed toward the center of the conduit. At the same time an annular ring of air defined by the outer edges of the blades is formed in a manner whereby the wet mixture is insulated from the conduit walls until the air and fuel 30 have become a substantially homogeneous colloidal gaseous mixture of fuel particles suspended in air.

The ends of both shafts 18 and 19 as viewed in Figure 4 extend through bearings in housing 35 14 and are squared, keyed, or otherwise shaped on their outer ends to receive geared segments 36 and 37, so that the blades 17 operate in unison and in opposite directions of rotation. Either shaft 18 or 19 is extended as at 38 for connection 40 to the throttle of the engine. The opposite end of either shaft 18 and 19 has a crank 39 keyed thereto, a rod 41 being connected to the crank and to the conventional carburetor pump.

Tapped hole 42 as shown in Figure 7 is provided 45 for receiving the spark control line, the smaller hole 43 connecting hole 42 with the intake conduit at a point immediately above one of blades 17 as shown in Figures 1 and 5. This position of hole 42 is in accordance with the usual spark control connection to the carburetor throttle whereby under small movement of the blades 17 away from the closed position, the hole 42 is transferred from an atmospheric location 50 to one subject to full engine vacuum so that the operation of the spark control will be correct.

Referring to Figures 8 and 9, a further preferred modified form of throttle valve is there illustrated wherein two blades 44 pivoted as shown in Figures 1 and 5 are formed to provide 60 in their closed position a truncated conical section 45 open at its lower end as shown in Figures 8 and 9. Disposed in this section and at a predetermined distance from the open bottom thereof is a jet 46 which connects with a fuel conduit 47 formed in a stream-lined rib 48 extending across the conduit and controlled by a needle valve 49.

When the throttle blades 44 are in closed position, as shown in Figure 9, by reason of the engine vacuum being effective on the lower end 70 thereof, a considerable flow of air is induced through the open cone 45 which, when the needle valve 49 is properly adjusted, draws the correct amount of fuel from jet 46 to provide a correct 75 air fuel ratio for the engine at idling speed. An

adjustable by-pass for additional air is provided at 51, a needle valve 52 being provided in connection therewith.

Due to the conical shape of aperture 45, there will be a gradation of pressure from the upper 5 end to the lower end, the lowest pressure being at the lower end. Thus at idling speed of the engine, jet 46 is not exposed to the full vacuum existing on the lower side of the throttle valve 44 but only to a portion thereof as determined 10 by the distance of the end of jet 46 from the upper end of hollow cone 45. As the throttle valve gradually opens, the conical effect of cone 45 is gradually eliminated, and jet 46 becomes exposed to the full vacuum of the intake manifold, 15 which increases the amount of fuel being drawn through the jet. This increase in the amount of fuel is accompanied by an increase in the quantity of air not only through the central opening of the throttle, but also around the outer edges 20 thereof so that the correct air fuel ratio is maintained at all times. Subsequent opening of the throttle 44 permits the vacuum in the intake manifold to become effective upon the main jet of the carburetor, positioned back in the venturi 25 or adjacent thereto and not shown in Figures 8 and 9 to carry the heavier loads. This modification is particularly desirable where it is desired to use only one auxiliary fuel jet.

In this modification, I have shown means 30 whereby the throttle and degasser and all of the modifications thereof illustrated herein may be readily installed in existing carburetor installations. In Figures 8 and 9, conduit 56 may be a portion of a carburetor from which the original throttle has been removed and containing a fuel supply line to the idling jets of the carburetor. To prevent interference by the openings 57 for the operating shaft of the original throttle and to use the original fuel supply jets 40 with my improved device, I provide a sleeve 58 of a diameter to fit snugly within the original carburetor conduit 56 to seal the throttle shaft openings 57. Sleeve 58 has a groove 59 in the wall thereof forming a passage with the inner 45 wall of conduit 56 to conduct fuel from the original idling jets of the carburetor to the new jets of my novel throttling device. This arrangement eliminates the necessity of providing new fuel supply lines when applying my invention to a 50 standard carburetor since the original lines are utilized.

It is to be understood that the sleeve arrangement shown in Figures 8 and 9 may be used both with the combined throttle and degasser 55 of this invention and with the throttling device of the present invention when no degasser is employed.

Referring to Figures 10 and 11, I have there shown a novel form of degasser for use with the governor and throttle of the present invention. As shown in Figure 10, a cross rib 26' is employed with a fuel conduit 27', jets 28' and 29', and needle valve 31' similar to parts 26 to 31 of Figure 3. The fuel conduit 27' is connected to a cross conduit 53 leading into a fuel supply conduit 54 controlled by needle valve 55.

The throttle blades 61, when in closed position, form an aperture 24 and a closed cup 25 as in the governor of Figure 1, and in addition 70 form an aperture 62 which fits closely about a conduit 63. Conduit 63 is connected by a conduit 64 to the interior of a chamber 65 formed by a housing 66 and a diaphragm 67. A spring 68 is provided in casing 66 to urge diaphragm 75

67 to the right as shown in Figure 10 with more power than can be developed in the chamber 65 by engine intake pressures. A counter-opposed spring 69, adjustable by means of a screw 5 and a locknut 72, opposes the action of spring 68 in a manner whereby at idling, the valve 55 which is connected to diaphragm 67 through a connecting rod 73, is held by the balance of the engine manifold pressure and springs 68 and 69 in a position sufficiently far off its seat to permit satisfactory idling of the engine.

10 Apertures 74 are provided in a casing 75, the latter being in threaded engagement with casing 66 to hold diaphragm 67 in the proper position. Casing 75 also serves to support adjustment member 71.

To appreciate the value of the degasser shown, it must be remembered that a degasser should be rendered effective or ineffective by a very small movement of the throttle 61 as in the order of .010 inch. Prior degassers have always employed mechanical means to multiply this movement, but such mechanical means have not been found satisfactory since it is practically impossible to mechanically multiply, with accuracy, such small movement of the throttle blade as .010 inch in a commercial carburetor.

In the operation of the degasser shown, assuming the engine to be idling or operating at 20 closed throttle and the device to be correctly adjusted, the throttle substantially seals the upper end of conduit 63 when the throttle blades are in closed position and subjects the entire lower end of the jet to the influence of the engine 30 manifold pressures. The adjustment of springs 68 and 69 will be such that needle valve 55 will be sufficiently far off its seat to permit the passage of fuel necessary to idle the engine. Thus there is no interference with the engine 35 at its idling speed.

If, however, the load conditions tend to drive the engine as for instance when a car is pushing an engine during deceleration or when descending a hill, the engine manifold pressure 40 will fall substantially lower than that at idling. Under such conditions, an undesired amount of fuel is drawn into the engine intake and results in so-called gassing. With the present device in proper adjustment, as the pressure in the engine manifold falls substantially lower than that at idling, this pressure is communicated through conduits 63 and 64 to the interior of chamber 65 to move diaphragm 67 to the left and close needle valve 55, thus shutting off all 45 fuel flow. No further fuel flow can occur at closed throttle until the manifold pressures again equal those for which the adjustment was made, that is, the manifold pressure at which the engine will idle, which will only be when the speed 50 of the engine again equals idling speed, at which point an even, reliable stream of idling fuel will be passed.

A further advantage of the present degasser is evident when it is considered that an engine may 55 idle at a vacuum of 18 inches, and still may have an open throttle or cracked throttle position that equals 20 inches of mercury. Obviously any balancing feature cannot function correctly when these conditions are present, for when at 60 idling pressures of 18 inches, the device must be on the point of functioning, it is apparent that it will be operated at 20 inches. Thus 20 inches on deceleration must work the device and 20 inches in running condition must not work the 65 device.

This situation is cared for by the present device. Assume that the engine is idling satisfactorily at 18 inches in the manifold and the space between conduit 63 and opening 62 in throttle 61 is closed enough to permit of a 17 5 inch vacuum in the chamber 65. The springs 68 and 69 are balanced to permit valve 55 to be off its seat sufficiently far to pass the necessary amount of fuel for the engine. Any decrease below 18 inches in the engine manifold will 10 shut the fuel off completely. At the same time if throttle 61 is opened .010 of an inch the vacuum within chamber 65 will fall off from 17 inches to approximately 13 inches, even though the manifold vacuum has increased from 18 to 21 15 or 22 inches. This is due to the 0.010 inch movement enlarging hole 62 around conduit 63, thereby allowing more air to pass therearound and reducing the effect of the engine manifold vacuum on the conduit 63 and the pressure in the chamber 65. Accordingly at cracked and all running throttle positions a proper supply of fuel is permitted to flow by valve 55, while during deceleration when the engine vacuum exceeds the normal idling vacuum and when the throttle valve 25 is closed, the fuel supply is cut off.

Briefly reviewing the operation of the degasser, it will be noted that when the throttle is in closed position, the size of conduit 63 and the size of aperture 62 formed by the closed throttle valve 30 are such that there is no leakage of air past conduit 63 and through aperture 62, the full manifold vacuum being effective upon diaphragm 67 in chamber 65. At this vacuum, springs 68 and 69 are adjusted so that they maintain needle 35 valve 55 in open position and permit of flow of fuel to the idling jet 28. Assuming that the car be driving the engine or the engine be decelerated, a manifold vacuum above idling vacuum is created at aperture 62 which vacuum is communicated to the interior of chamber 65 to draw diaphragms 67 to the left and close needle valve 55 to shut off the fuel flow. This operation of course occurs when the throttle valve remains in closed position.

40 Assuming that the throttle valve is moved toward open position and the vacuum in the intake manifold is higher than idling vacuum, aperture 62 will then not be closely fitted about conduit 63 and will permit atmospheric air to flow from the upper side of the throttle through the now enlarged aperture 62. This reduces the effect of the engine intake vacuum upon jet 63 and increases the pressure in chamber 65 to move needle valve 55 to open position.

45 It will be noted that the degasser is exceedingly sensitive to a very slight movement of the throttle during a critical range, this movement of the throttle resulting in a very quick action of the degasser valve so that there is no interruption in fuel supply except when intended. It is therefore apparent that the present invention provides a degasser which operates satisfactorily under all conditions of operation without need of mechanical aid, the degasser being 60 extremely sensitive and responsive to the range 65 of conditions within which it is designed to operate.

In Figure 11, I have shown a preferred method 70 of assembly of the present invention, the method being shown by way of example in connection with the degasser combination. The housing 82 is formed with opposing slots 83 having tapered side walls as shown. The rib 26 of Figure 3 or rim 26' of Figure 10 is formed to carry the jets 75

and the degasser therewith, if used, and is shaped at its outer ends to fit within the slots 83. Since housing 82 is preferably die-cast, the ribs 26 or 26' may be placed within slots 83 and tapped slightly to obtain a tight fit.

This method of assembly is relatively simple and permits ribs 26 or 26' to be machined and finished before they are assembled with the governor. Obviously this effects economies in manufacture since the ribs would be difficult to machine if cast with the governor. Moreover, this arrangement permits the ready substitution of one type of rib for another.

In Figures 12 and 13 I have illustrated further preferred modifications of the degasser of my invention. In Figure 12 a throttle 14 comprising two blades is designed so that at closed position of the throttle an aperture 15 of predetermined size is formed at the bottom 20 of the throttle immediately below a conduit 76 corresponding to the conduit 63 of Figure 10. The under edges of the conduit are beveled as shown at 77 to engage the adjacent surface of the throttle.

Figure 13 discloses a somewhat analogous modification wherein a throttle blade 78 is shown, one wing of which is provided with an aperture 79. Disposed immediately above aperture 79 is a conduit 81 the lower portion of which is curved 30 so as to provide a substantially abutting engagement with the upper surface of the throttle. Instead of curving conduit 81, the lower surface thereof may be cut transversely at an acute angle 35 to the conduit axis to provide a surface parallel to and fitting against the adjacent surface of the throttle when closed.

In Figures 14 and 15, the degasser of my invention is shown as applied to a carburetor of the updraft type with the usual throttle valve of the butterfly type. With such types of throttles, it has been difficult to obtain satisfactory operation of the degasser since means hitherto employed has not been sufficiently sensitive to the different conditions created by the throttle during its 45 course of movement, particularly from a fully closed toward open position. While prior devices have attempted to increase the sensitivity of the degasser by mechanical means primarily as by involved systems of levers and linkages, 50 none has proven as satisfactory in actual operation as the present degasser wherein mechanical means are almost entirely eliminated and a very fast action of the degasser is obtained through a predetermined and relatively slight movement 55 of the throttle.

Referring to Figure 14, a carburetor conduit is shown at 84 with a venturi 85, and a butterfly valve 86. A fuel supply line 87, preferably leading from the float chamber of the carburetor, 60 has a valve seat 88 therein and connects with jets 89 and 91 for feeding fuel at idling and light loads. A diaphragm housing is provided at 92, the housing being either cast integral with the carburetor or secured thereto by suitable 65 means. Housing 92 is provided with a cover 93 having apertures 94 leading to the atmosphere, a diaphragm 95 of rubber, Duprene or similar material being secured therebetween. Springs 96 and 97 are provided on opposite sides of diaphragm 95, spring 96 being adjustable by a plug 98 threadedly mounted in cover 93. A needle valve 99 is mounted on the right side of diaphragm 95 to engage valve seat 88. A conduit 101 leads from housing 92 to a connection 102 70 to the carburetor conduit immediately adjacent

an edge of throttle 86 when closed. The point of connection of conduit 101 is such that when throttle 86 is closed the vacuum above throttle 86 or the vacuum in the engine manifold is effective upon the right side of diaphragm 95. It 5 will be noted that the connection 102 is at the point where the throttle blade has a maximum movement for a predetermined angle of oscillation. This location contributes to the sensitivity and responsiveness of the degasser. 10

The springs 96 and 97 are so adjusted that when the throttle is closed and the engine is idling, the vacuum in the engine manifold is insufficient to move the diaphragm to the right to close valve 99. When the engine is decelerating 15 or the car is driving the engine as when going down hill, the vacuum in the engine manifold will be greater than that at idling and diaphragm 95 will move to the right to shut off the fuel supply to jets 89 and 91. When throttle 86 is 20 opened even to a very slight degree, connection 102 will be subject to the pressure effective on the lower side of throttle 86 and diaphragm 95 will quickly move to the left to open valve 99 and permit the free flow of fuel to jets 89 and 91. The 25 quick response of diaphragm 95 is desirable to prevent an interruption in fuel flow when not desired.

To increase the sensitivity of the degasser, the edge of throttle 86 immediately adjacent connection 102 preferably is cut away to form a knife edge 103. Thus only a very slight movement of throttle 86 is sufficient to transfer connection 102 from the effect of the vacuum above the throttle to the pressure below the throttle and the degasser is correspondingly rendered more sensitive. 30

It will therefore be seen that the present invention provides a degasser that is extremely sensitive and responsive to the range of conditions within which it is designed to operate without the aid of mechanical multiplying devices or the like. 40

The invention may be embodied in other specific forms without departing from the spirit or essential characteristics thereof. The present embodiment is therefore to be considered in all respects as illustrative and not restrictive, the scope of the invention being indicated by the appended claims rather than by the foregoing description, and all changes which come within 50 the meaning and range of equivalency of the claims are therefore intended to be embraced therein. 45

What is claimed and desired to be secured by United States Letters Patent is:

1. In a carburetor, a conduit; a venturi in said conduit; a main fuel jet in said venturi; a throttle in said conduit downstream of said main jet comprising two blades, pivoted on axes spaced from the conduit walls, and spaced from one another when in open position, each of a size to close approximately one-half of said conduit and arranged to engage along a line passing through the center of said conduit whereby closing of said conduit along three lines is accomplished, said blades being inclined toward one another and toward the axis of said conduit in a direction with the fluid flow; and an idling jet to introduce fuel at a point along said central line of closure, the inner edges of said blades being recessed to form 70 an opening for said idling jet. 60

2. In a carburetor for an internal combustion engine, a conduit; a venturi in said conduit; a main fuel jet in said venturi; a throttle in said conduit downstream of said main jet comprising 75

2. A plurality of individual blades arranged to meet and effect a closure therebetween substantially along a diameter of said conduit, said blades being pivoted on axes spaced from the conduit walls to effect closing of said conduit along three lines; and a jet to discharge fuel for idling purposes into said conduit at a point substantially midway of said diameter, said blades in closed position defining an aperture surrounding said jet whereby said jet is subject to the intake manifold vacuum of said engine when said throttle is closed.
3. The combination set forth in claim 2 wherein said aperture is of a size to permit a restricted flow of air around said jet to further increase the flow of fuel therefrom and atomize said fuel.
4. The combination set forth in claim 2 wherein means effective in closed position of said throttle to mix air with said fuel prior to its delivery from said fuel discharge means to aid in the atomization thereof is provided, said means including a second fuel jet positioned upstream of said blades when in closed position and subject to the pressure on the downstream side of said blades when said blades are in open position.
5. In a carburetor for an internal combustion engine, a conduit; a throttle in said conduit comprising a plurality of blades mounted on individual axes and spaced from one another when in open position to provide lines of closure at approximately the center of said conduit and at the sides of said conduit; and a fuel jet positioned approximately in the center of said conduit at said central line of closure whereby the fuel is discharged and atomized at a point substantially in the center of said conduit, said blades being arranged to close said jet when in closed position; and an idling jet to discharge fuel into said conduit when said blades are in closed position.
6. In a carburetor for an internal combustion engine, a conduit; a throttle in said conduit comprising a plurality of blades arranged to effect a closure along a line passing substantially through the center of said conduit; and a plurality of fuel jets positioned to discharge fuel adjacent said line of closure, one of said jets being positioned to discharge fuel on the downstream side of said throttle when the latter is in open or closed position, and another of said jets being positioned to be open to the upstream side of said throttle when the latter is closed whereby it is subject to substantially atmospheric pressure at closed throttle position, the latter jet being transferred from atmospheric pressure to the pressure downstream of said throttle by movement of said throttle toward open position.
7. In a carburetor for an internal combustion engine, a conduit; a throttle in said conduit comprising a plurality of blades arranged to effect a closure on a line extending substantially through the center of said conduit, each of the contacting edges of said blades comprising a notch and a half-cup section whereby in closed position said blades define an aperture of predetermined size and a cup opening against the direction of fluid flow; a fuel supply line; a jet connected to said line extending into the aperture formed between said blades, and a second jet connected to said line opening into said cup whereby in closed position of said throttle, the first jet functions to induce a flow of fuel from said fuel supply line and a flow of air from said second jet.
8. The combination claimed in claim 7 wherein

means is provided to close said fuel supply line when said throttle is in closed position and the vacuum in the intake manifold is greater than predetermined normal idling vacuum comprising a pressure responsive device connected to said passage through a conduit having an orifice at a point immediately adjacent an edge of said throttle when in closed position whereby when said throttle is in closed position, said orifice is subject to the vacuum on the engine side of the throttle, and when said throttle is cracked open a very slight amount, said orifice is subject to a higher pressure by reason of the pressure existing on the upstream side of said throttle.

9. In a carburetor having a conduit therein connected to the intake manifold of an internal combustion engine; a throttle comprising a plurality of separately pivoted blades spaced from one another when in open position, each of a size to close approximately one-half of said conduit and arranged to engage along a line passing through the center of said conduit; a fuel jet adjacent the closure line of said blades when in closed position whereby the flow of fuel from said jet is metered by said throttle; a fuel supply line to said jet; pressure responsive means to control said fuel supply line, said pressure responsive means being connected to said conduit by a second conduit having an orifice at a point adjacent the closure line of said blades when the latter are in closed position and arranged to be exposed to the pressure in the intake manifold when the throttle is in closed position, said means being arranged to close the fuel supply line when the throttle is closed and the pressure in said intake manifold is below predetermined normal idling pressure, and to open said fuel supply line when said throttle moves toward open position and said orifice is subjected to higher pressure.

10. In a carburetor having a conduit connected to the intake manifold of an internal combustion engine; a throttle comprising a plurality of separately pivoted blades spaced from one another and from the sides of said conduit when in open position, each of a size to close approximately one-half of said conduit and arranged to engage along a line passing through the center of said conduit whereby closing of said conduit along three lines is accomplished; a fuel jet adjacent the central closure line of said blades, said blades being notched to form an aperture in closed position permitting flow of fuel from said jet to the downstream side of said blades; a fuel supply line to said jet; pressure responsive means to control said fuel supply line, said pressure responsive means being connected to said conduit at a point adjacent the central closure line of said blades, said blades being formed to provide an aperture in closed position connecting said pressure responsive means to the engine vacuum and sealing said connection from the pressure upstream of said blades.

11. In a carburetor for an internal combustion engine, a conduit; a throttle in said conduit; a plurality of fuel jets positioned upstream of said throttle, said throttle being provided with an aperture to connect at least one of said jets to its downstream side when in closed position, said aperture being positioned and of a size to closely fit about said jet when said throttle is in closed position to subject said jet to substantially the full effect of the pressure downstream of said throttle, the remaining jet being subjected to the pressure upstream of said throttle when the latter is in closed position.

12. In a carburetor for an internal combustion engine, a conduit; a throttle in said conduit; a fuel supply line; a jet upstream of said throttle connected to said fuel supply line and positioned to be subject to the pressure on the downstream side of said throttle through an aperture in said throttle when in closed position, said aperture being positioned and of a size to closely fit about said jet when said throttle is closed; and a second jet upstream of said throttle connected to said fuel supply line and positioned to be subject to the pressure on the upstream side of said throttle when the latter is in closed position whereby in closed position of said throttle, said downstream pressure functions to induce a flow of fuel from said supply line and a flow of air from said second jet, both through said first jet.
13. The combination claimed in claim 12 wherein means is provided to close said fuel supply line when said throttle is in closed position and the vacuum in the intake manifold of said engine is greater than predetermined idling vacuum comprising a pressure responsive device connected to said passage by a conduit having an orifice at a point immediately adjacent an edge of said throttle when in closed position whereby when said throttle is in closed position, said orifice is subject to the vacuum on the engine side of said throttle and when said throttle is cracked open a very slight amount, said orifice is subject to a higher pressure by reason of the pressure existing on the other side of said throttle.
14. In an internal combustion engine, a carburetor having a passage for conveying fuel and air to the engine; main and idling fuel supply means; a throttle for opening and closing said passage; means for shutting off the idling fuel supply means when said throttle is at closed position and the engine develops a vacuum in excess of predetermined normal idling vacuum, and for automatically opening said idling fuel supply means when said throttle is opened, said last-mentioned means comprising a pressure responsive device connected to said passage by a conduit having an orifice at a point immediately adjacent an edge of said throttle when in closed position whereby when said throttle is in closed position, said orifice is subject to the pressure on the engine side of said throttle and when said throttle is cracked open a very slight amount, said orifice is subject to a higher pressure because of the pressure existing on the other side of said throttle.
15. In combination with a carburetor comprising a conduit and a throttle in said conduit; idling fuel supply means; means whereby said idling fuel supply means is shut off whenever at closed throttle the pressure downstream of said throttle falls below predetermined normal idling or closed throttle pressure, said means comprising pressure responsive means connected to said carburetor conduit by a conduit having an orifice subject to substantially intake manifold vacuum when said throttle is closed and positioned immediately adjacent a lip of said throttle when in closed position so that slight motion of said throttle from closed toward open position immediately interrupts the connection from the pressure in the intake manifold and subjects said orifice to a pressure substantially higher than that in the intake conduit to quickly and fully open said fuel supply means.
16. In combination with a carburetor having a conduit connected to the intake of an internal combustion engine, a throttle of the butterfly valve type; an idling fuel jet adjacent one edge of said throttle whereby in closed and nearly closed position the flow of fuel from said jet is metered by said throttle; an idling fuel supply line to said jet; and pressure responsive means to close said idling fuel supply line, said pressure responsive means being connected to said carburetor conduit by a conduit having an orifice immediately adjacent an edge of said throttle when the latter is in closed position and arranged to be subject to the pressure in said intake when said throttle is in closed position, said means being arranged to close said idling fuel supply line when said throttle is closed and at a pressure in said intake less than the predetermined normal idling pressure, and to open said idling fuel supply line as said throttle moves away from closed position and said orifice is thereby subjected to higher pressure.
17. In a carburetor for use with an internal combustion engine, a throttle; means adjacent an edge of said throttle when in closed position to provide fuel when said engine is idling or operating under light load; means to shut off the supply of fuel when said throttle is in closed position and the vacuum downstream from said throttle exceeds that of predetermined normal idling vacuum, and means to connect said shut-off means to said carburetor adjacent an edge of said throttle when in closed position, the adjacent edge of said throttle being formed as a relatively thin section relative to the thickness of the remainder of said throttle to increase the sensitivity of said fuel shut-off means.
18. A carburetor for an internal combustion engine comprising a passage for conducting fuel to said engine; a throttle in said passage; a conduit having an orifice opening into said passage immediately adjacent an edge of said throttle when in closed position to supply fuel at idling and under light load; means connected to said passage to shut off the flow of fuel to said supply means when said passage is closed by said throttle and the engine develops a vacuum in excess of predetermined normal idling vacuum, said throttle being positioned to control said shut-off means and to meter the fuel mixture from said supply conduit.
19. A carburetor for an internal combustion engine comprising a passage for conducting fuel to said engine; a throttle in said passage for controlling the flow of fuel therethrough; a jet to supply fuel at idling and under light loads opening into said passage at a point adjacent an edge of said throttle when in closed position to be controlled by said throttle; means connected to said passage by a conduit having an orifice to shut off the flow of fuel to said jet when said passage is closed by said throttle and the engine develops a vacuum in excess of predetermined normal idling vacuum, said orifice being positioned immediately adjacent an edge of said throttle when in closed position so that operation of said means will be dependent upon the position of said throttle.
20. A carburetor for an internal combustion engine comprising a passage for conducting fuel to said engine; a throttle in said passage for controlling the flow of fuel therethrough; a jet for supplying fuel to said engine at idling and under light load; and means to shut off the fuel supply to said jet when said throttle is in closed position and the engine develops a vacuum in excess of predetermined normal idling vacuum, said means being connected to said passage by a conduit having an orifice at a point immediately adjacent

the downstream lip of said throttle when in closed position whereby operation of said means will be dependent upon the position of said throttle.

21. A carburetor for an internal combustion engine having main and idling fuel supply means; a passage for conducting fuel to said engine; a throttle for opening and closing said passage; and means for shutting off said idling fuel supply means when said throttle is at closed position 10 and the engine develops a vacuum in excess of predetermined normal idling vacuum and for automatically opening said idling fuel supply means

when said throttle opens comprising a pressure responsive device connected to said passage by a conduit having an orifice at a point closely adjacent a portion of said throttle when in closed position whereby said connection is connected to the engine side of said throttle when said throttle is in closed position, and on movement of said throttle toward open position to create an opening in the order of 0.01 inch, said connection is broken sufficient to render said shut-off means 10 inoperative. 5
